AMMUNITION

John D. Howell, Ilion, N. Y., assignor to Remington Arms Company, Inc., Bridgeport, Conn., a corporation of Delaware

Application December 13, 1945, Serial No. 634,743

2 Claims. (Cl. 102—80)

1

This invention relates to projectiles and, in particular, to an improved device for arming explosive and pyrotechnic projectiles. More especially, the invention relates to an improved detent for use in a projectile embodying a rotor type fuse.

The projectile shown and described is a small arms bullet, but it will be understood that this is for the purpose of illustration only and that the invention may be used with other types of fused projectiles and includes all modifications within the scope of the appended claims.

Fuses of various types have been used extensively in projectiles of large caliber shells and to some extent in the projectiles of cartridges of small caliber, such as 20 mm. cartridges and the 12 mm. cartridges used by both the Germans and Japanese. A more recent development is a 20 mm. cartridge embodying a rotor type fuse which, briefly, comprises a truncated sphere freely mounted in a substantially rectangular slot in the nose or cap of the projectile. The axis of rotation of the rotor passes through the geometrical center of the two flats of the rotor and is disposed at right angles to the longitudinal axis of the projectile. An aperture is provided in the rotor to receive a detonator, the axis of the aperture being substantially perpendicular to the axis of rotation of the rotor. On firing the cartridge, the rotation or spin of the projectile about its longitudinal axis sets up an unbalanced force couple in the rotor which swings the latter about its axis of rotation so as to arm the projectile by aligning the detonator with a firing pin provided in the end of the cap. Normally, however, that is to say, before the projectile has been fired, the detonator is held out of axial alignment with the firing pin by providing a suitable detent which temporarily holds the rotor from turning about its axis.

One type of detent currently in use comprises a substantially rectangular block supported to slide freely in a longitudinal slot in the fuse cap, the slot being asymmetrical with respect to the longitudinal axis of the projectile. The slide block has a laterally projecting shear pin arranged to engage in an aperture of the rotor to temporarily hold the latter from rotating. When the projectile is fired, the inertia of the block is sufficient to cause the block to set back or slide rearwardly in its slot relative to the rotor and thus shear off the pin and free the rotor.

Although this type of detent has had some use, it embodies a number of closely fitting parts which are expensive to manufacture and difficult

2

to assemble. Moreover, the design of the detent is basically undesirable in that the parts are asymmetrical with respect to the longitudinal axis of the projectile and, hence, interfere with the balance and accuracy of the projectile during flight.

An object of this invention is to provide an improved fuse for projectiles and, more especially, an improved device to prevent the fuse from arming until the projectile has safely traversed the length of the barrel. A further object is to provide a rotor type fuse with an improved detent which is simple to manufacture, simple to assemble and which is symmetrical with respect to the major axis of the projectile so as to insure the accuracy of the projectile during flight.

These and other objects, features and advantages of the invention will be described herein-after in detail, reference being made to the accompanying drawing in which:

Fig. 1 is a side elevation in section of a projectile embodying the improved fuse assembly of this invention, the elements being in safe position.

Fig. 2 is a sectional view of the fuse cap before assembly on the body of the projectile and taken in the direction of arrows 2—2 of Fig. 1 showing the rotor and detent disk assembled in the cap. An aperture is shown in the rotor to receive a detonator.

Fig. 3 is an end view of the cap in the direction of arrows 3—3 of Fig. 2.

Fig. 4 is a side elevation of the rotor.

Fig. 5 is an end elevation of the rotor.

Fig. 6 is a fragmentary view of the projectile shown in Fig. 1, but with the elements of the fuse in armed position.

Referring to the drawing, the projectile shown in Fig. 1 comprises a hollow cylindrical body or core 10, the heel end 11 of which is of reduced diameter and provided with a knurled surface which, in the embodiment shown, comprises a plurality of spaced bands 12 of knurling. A counterbore 13 is shown in the rear end of the core aperture 14 and is adapted to receive relatively heavy material, such as lead granules or lead slugs 15 for the purpose of providing a projectile of the proper weight. A standard sabot 16 is shown pressed over the heel end of the core to which it is firmly secured by the bands of knurling 12.

The forward end of the core has a conical shoulder 17, the base of which is spaced from a slightly tapered surface 18, adjacent the forward end of the core, by an annular groove 19 having

a relatively fine knurl 20 in the bottom thereof. The central aperture 14 of the core is adapted to be substantially filled with an explosive or pyrotechnic charge and is provided with a depression at its front end for the purpose hereinafter described.

The nose portion of the projectile constitutes the fuse and comprises a cap indicated generally at 21 and which, in the present embodiment, is formed from a zinc blank by a cold extrusion process. It will be understood, however, that other materials and methods may be used for forming the fuse cap. The profile of the cap constitutes the ogive of the projectile and before assembly on the core has a skirted base portion 22. When assembled on the core, the skirt 22 will be blended into the tapered surface 18 of the core as shown in Figs. 1 and 6. The cap has a relatively solid tip 23 provided with an axial firing pin aperture 24. Rearwardly of the solid tip 23 is a recess indicated generally at 25 which is open at its rear end and of substantially rectangular cross section, see Fig. 3. This recess comprises substantially parallel planar side walls 26 (see Figs. 2 and 3) and top and bottom walls 27, the latter being of arcuate cross section. The forward end of the recess is substantially blind and comprises a semicircular wall 28, see Fig. 5, which is formed by quadrants 27' of the upper and lower walls 27. An aperture 29 is provided in the forward wall of the recess in axial alignment with the firing pin aperture 24 and of slightly greater diameter so as to form a substantially square shoulder 30 with the rear end of the firing pin aperture 24.

The rear end of the recess 25 opens into a relatively large counterbore 32, the forward end of which forms a substantially square shoulder 33 with the rear end of the recess 25. The profile of the counterbore comprises a cylindrical wall section 34 at the forward end of the counterbore, an annular rib 35 of rounded cross section at the rear end of the counterbore, corresponding to the skirted portion 22 of the cap, and an annular taper 36 intermediate the cylindrical wall section and the annular rib.

A firing pin 37 is shown in the aperture 24 in the nose of the cap. In this embodiment, the pin 37 comprises a shank portion 37' which makes a smooth sliding fit in the aperture 24 and which is provided on its forward end with a radius 38. The rear end of the shank comprises a conical detent 39 having a substantially square flange 40 at its base of greater diameter than the firing pin aperture 24. The firing pin is assembled in the nose of the cap by inserting the rounded end of the firing pin into the rear end of the firing pin aperture and sliding the pin forwardly until its flange 40 abuts the shoulder 30. This construction prevents the firing pin from moving forwardly and dropping out of the nose of the cap, the firing pin being enabled to move rearwardly freely on striking a target so as to fire a detonator as hereinafter described.

Mounted freely in the recess 25 is a rotor 42, see Figs. 4 and 5, which may be formed of brass or other suitable material and which is shaped in general like a truncated sphere having two flat substantially parallel surfaces 43 at opposite ends of its minor axis (m). The latter is hereinafter referred to as the axis of rotation of the rotor and, when assembled in the cap, is substantially perpendicular to the major axis of the projectile. The geometry of the rotor is such that when it is mounted in the recess 25 of the

cap, the flats 43 of the rotor are in juxtaposition to the corresponding planar side walls 26 of the recess 25 while the spherical surfaces 45 of the rotor fit into the arcuate top and bottom walls 27 and semicircular front wall 28 of the recess, as shown clearly in Figs. 1 and 2.

As shown, a substantially cylindrical aperture 46 is provided on one of the major diameters of the rotor and is adapted to contain a detonator charge 47 which is held in the aperture by suitable sealing disks, such as foils 48. The density of the detonator charge 47 is different than the density of the material of the rotor 42 and hence insures a force couple to rotate the rotor in the manner hereinafter described.

Referring to Figs. 1 and 2, the periphery 45 of the rotor is provided with two diametrically opposite pairs of conical notches 49, each notch being adapted to receive the detent 39 of the firing pin. The arrangement of these notches is shown in Figs. 1 and 4 and is such that, when one of these notches is engaged by the detent of the firing pin, the longitudinal axis of the detonator 47 will be held at an angle of substantially 75° with the major axis of the projectile and out of axial alignment with the firing pin.

Suitable means for holding the rotor forward in its recess 25 so that the detent 39 will fit in one of the rotor notches 49 is shown at 50 and comprises a detent washer having a concentric flash hole 52. The detent washer is preferably formed of copper having a soft temper and is normally convex in shape (see dotted lines in Fig. 2) and adapted to seat on the square shoulder 33 of the cap. During assembly of the fuse, as hereinbefore described, the convex washer is flattened thereby forcing the peripheral edge of the washer tightly against the cylindrical wall section 34 of the counterbore so as to secure the washer firmly against the shoulder 33. In its assembled position, the flattened body portion of the washer is in juxtaposition to the rear end of the rotor as shown in Figs. 1 and 2 and serves to hold the rotor forwardly and to prevent rearward movement thereof in its recess 25. The firing pin detent 39 will thus be enabled to fully engage in one of the conical notches 49 of the rotor to prevent the latter from rotating about its minor axis.

The assembly of the projectile and fuse is relatively simple and quickly accomplished. The detonator mixture 47 is loaded into the cylindrical aperture 46 of the rotor and covered at its opposite ends with the seals or foils 48. The firing pin is inserted into the aperture 24 in the nose of the cap in the manner described above. The rotor is then inserted into the rotor recess 25 and shaken gently until one of the four conical notches 49 slips over the firing pin detent 39. The flexible washer 50 is then placed on its seat with its convex side out and flattened, thus securing it firmly in place and holding the rotor forwardly in its recess. The firing pin detent, rotor-detonator, and soft-tempered detent washer thus form an integral fuse assembly within the cap 21. The hollow body of the core 10 is loaded with its explosive or pyrotechnic charge 53 and a suitable number of grains of lead in the form of a lead-slug or slugs 15 are provided in the tail-end for properly weighting the projectile. It will be noted that there is a slight depression 54 in the forward end of the powder charge. For successful operation, the powder adjacent the depression 54 should be compressed hard enough or other means provided to hold the shape of the depression so as to prevent its breakdown at any time prior to

the arming of the projectile. The loaded core is then pressed heel end first into the sabot cup 16. The fuse assembly is then secured to the core by supporting the cap, point down, in a profile die and pressing the forward end of the core into the rear end of the cap thereby to seat the conical shoulder 17 of the core against the correspondingly tapered shoulder 36 of the cap; and to swage the skirted portion 22 of the cap inwardly radially so that its annular rib 35 locks securely in the annular knurled groove 19 of the core, its outer surface being blended smoothly into the external tapered surface 18 of the core.

The fuse of the projectile functions as follows: Immediately after firing the projectile the inertia of the relatively heavy rotor 42 exerts sufficient force against the center of the relatively soft detent washer 50 to distort the washer as shown in Fig. 6 and release the rotor which moves rearwardly out of its recess 25. Rearward displacement of the washer and rotor is permitted by the depression 54 in the forward end of the powder charge 53, this depression being of such depth that the rotor 42 may set back sufficiently to disengage the firing pin detent 39 from one of the conical notches 49 of the rotor. The rotor is thereupon unlocked and free to rotate about its minor axis (n). Initially, however, that is to say, while the projectile is moving down the first half of the barrel length, the acceleration of the projectile is so high and the centrifugal forces so low that the rotor is held back substantially immobile against the washer, this immobility of the rotor being further enhanced by the friction between the rotor and washer. Consequently, the rotor does not rotate into position to arm the projectile, i. e. to align the detonator with the firing pin. As the projectile passes through the second half of the barrel length, its acceleration decreases and the centrifugal force increases rapidly and reaches a magnitude such that an unbalanced force couple will be set up in the rotor, due to the difference in density of the rotor and its detonator, which will cause the rotor to turn. By properly proportioning the rotor 42 and initially setting the longitudinal axis of detonator 47 at an angle of substantially 75° with the major axis of the projectile, the projectile will have left the muzzle of the barrel by the time the detonator 47 is fully aligned with the firing pin 37. There is, therefore, no likelihood of the projectile exploding while

still in the barrel of the firearm, that is to say, the projectile is bore safe. After leaving the muzzle of the firearm, the inertia of the rotor acting in conjunction with the deceleration of the projectile will cause the rotor to creep forwardly until the detonator is in contact with the firing pin detent and hence insure a supersensitive action. It is clear, however, that the projectile is safe against exploding by handling since the detonator 47 is normally securely held out of line with both the firing pin 37 and the flash hole 52 of the detent washer until the projectile is armed. After the projectile has been armed and on striking a target the firing pin 37 and rotor 42 will be driven together violently, thereby exploding the detonator 47 and sending hot gases and flame through the flash hole 52 of the washer 50 to ignite the powder charge 53 within the core of the projectile.

20 What is claimed is:

1. A projectile fuse comprising a housing having therein a rearwardly opening recess and a forwardly opening aperture communicating with said recess, a shouldered firing pin in said aperture and projecting into said recess, a rotor in said recess containing a detonator, and a normally flat surfaced, edge supported soft metal disk press fitted into said recess in engagement with the rear portion of the rotor and normally holding said rotor in unarmed interengagement with said firing pin, said member being adapted for plastic deformation by the setback of said rotor incident to firing and to thereafter support said rotor free of said firing pin for centrifugal rotation to armed position.

2. A device according to claim 1 secured to a projectile containing a charge to be ignited by said detonator, the adjacent surface of such charge being of concave configuration and affording a support for said plastically deformable member when deformed.

JOHN D. HOWELL.
